UNITED STATES PATENT OFFICE.

WILLIAM L. BLISS, OF NIAGARA FALLS, NEW YORK, ASSIGNOR, BY MESNE ASSIGNMENTS, TO THE U. S. LIGHT AND HEAT CORPORATION, OF NIAGARA FALLS, NEW YORK, A CORPORATION OF NEW YORK.

HAND-HOLE COVER FOR GENERATORS.

1,157,497.

Specification of Letters Patent.

Patented Oct. 19, 1915.

Application filed January 9, 1912. Serial No. 670,277.

To all whom it may concern:

Be it known that I, WILLIAM L. BLISS, a citizen of the United States, residing at Niagara Falls, in the county of Niagara and 5 State of New York, have invented new and useful Improvements in Hand-Hole Covers for Generators, of which the following is a full, clear, concise, and exact description, reference being had to the accompanying 10 drawing, forming a part of this specification.

My invention relates to a hand hole cover for a generator.

Where the construction of a generator field frame or casing is such that the brushes 15 and commutator are completely inclosed in order to protect the same against dust, moisture or other foreign elements, it is desirable to provide ready access to said brushes and commutator for the purpose of inspection, 20 adjustment and renewal.

The object of my invention is to provide means which permit ready access to the brushes, commutator and associated parts, which means, however, shall effectively 25 protect these parts against the intrusion of dust and dirt.

In the accompanying drawings I have 30 illustrated a very simple, effective and practical embodiment of the invention. It consists of a hand hole cover which is very light and strong and which may be quickly removed from and quickly applied to the casing of a car lighting generator. I have 35 illustrated a car lighting generator because the generators in this class of service are usually mounted on a car truck, and accordingly are normally subjected to the objectional effects of an excessive amount of dust and dirt, whereby the need for some 40 device for effectually barring these deleterious elements is especially great.

Figure 1 is an elevation of a car lighting generator having a hand hole cover in the form of a flexible band applied thereto. 45 Fig. 2 is a sectional elevation taken on the line 2—2 of Fig. 1. Fig. 3 is an elevation of a detail.

The car lighting generator 1 may be provided with any well known type of brush 50 mechanism which is preferably concealed in the reduced end portion 2. This end portion, as illustrated, is circular in outline and is provided preferably with two large openings 3 on opposite sides thereof. Of course,

the number of openings may be varied to 55 suit the particular type of generator, the use of two holes of about the relative size and location of those illustrated in the drawings being particularly useful in connection with a four pole machine.

In order to cover the openings 3 and to 60 prevent the entrance of dust and moisture, I provide an encircling band or belt 4 preferably of cotton adapted to completely surround the circular end portion 2 and of a 65 width sufficient to cover the openings. This band is preferably re-inforced by a metallic backing 5 of any suitable material. Galvanized sheet iron is very satisfactory. The sheet iron backing is preferably riveted to 70 the cotton belt at a sufficient number of points to effect a substantially unitary structure of these two elements. Among the rivets used I preferably provide four pairs of rivets 6 much larger than the remaining 75 rivets, and having preferably conical heads projecting radially inward. These rivets are so located that their integral projecting heads are adjacent the walls which determine the ends of the openings 3, as shown 80 clearly in Fig. 2. Accordingly, the rivets act as guides in properly locating the belt in such a manner that the same may be effectively tightened without leaving any openings or cracks for the entrance of dust. In 85 fact, the design of the parts is such that it is practically impossible to adjust the belt clamping device unless the rivets 6 are dropped into the openings 3. If these rivets happen to rest on the circular wall shown 90 in Fig. 2, the effective circumference of the belt would be increased to such a degree as to render the engagement of the belt clamping elements temporarily out of the question.

The belt clamping elements include, in 95 general, a suitable bracket 7 riveted near one end of the belt and a wrench or handle 8 preferably riveted at 9 to an eye or opening formed by turning in and riveting one end of the sheet iron backing 5. This construction is clearly illustrated in Figs. 2 and 3. The connections between the handle 8 and the pivotal point 9 include a T-shaped bolt 10 having a screw-threaded end received in an end of the handle 8. The bracket 7 is provided with a pair of abutments or jaws 11, having an opening between the same, and each having a turned-over outer extremity

or hooked portion 12. Said opening is adapted to receive the bolt 10 loosely therein, but is sufficiently narrow, however, to prevent the abutting end 13 of the wrench from passing therethrough. It is apparent that by revolving the handle or wrench 8 in a direction tending to unscrew the same from the threaded end of the bolt 10, the belt as a whole will be loosened, and the bearing 10 end 13 of the wrench will be backed away from the abutments 11, whereby said wrench as a whole may readily be swung up or lifted to approximately the dotted line position shown in Fig. 2, whereupon the encircling 15 band may be readily lifted from the generator casing. In order to replace the belt the above operation is simply reversed and the wrench is tightened until the cotton belt is drawn firmly down over the openings, 20 thereby effectively closing said openings. It should be noted that the handle portion 8 is preferably bent at a considerable angle with the main body portion of the wrench, whereby the weight of said handle tends to 25 maintain the same in a pendant position and prevents the gradual unscrewing of the same, due to continued jarring or vibration. Furthermore, the provision of the hooked portion 12 insures a positive locking engagement 30 of the respective end portions of the belt. At the same time these hooked projections 12 are so short that only a few revolutions of the wrench are necessary in order to withdraw the end 13 a sufficient distance 35 to permit the handle to be lifted and the parts entirely disengaged.

Although I have illustrated my preferred construction as applied to a car lighting generator, of course it is not limited to use 40 with this type of generator. Furthermore, I do not desire to limit myself to the various details of construction shown and described, but desire to cover suitable equivalent means, where such means fall within 45 the scope of the appended claims.

What I claim as new and desire to secure by Letters Patent of the United States is:

1. In combination with a generator casing provided with inspection openings therethrough, a flexible band encircling said casing and covering said openings, means for detachably uniting the ends of said band and drawing the same together, and means for positioning the ends of said band on said 50 casing to prevent the joint in the band from registering with an inspection opening.

2. In combination, a generally cylindrical casing, an inspection opening therethrough, a flexible strip encircling the casing and closing said opening, means for positioning 55

said strip circumferentially with respect to said casing to insure complete closure of said opening, and means for drawing the ends of said strip together.

3. In combination, a cylindrical casing, 65 inspection openings therethrough, a flexible strip surrounding the casing and forming an inclosure for said openings, means for positioning said strip circumferentially with respect to said casing to insure complete closure of said openings, and a separable fastener for adjustably drawing the ends of said strip together and detachably holding them in adjusted position.

4. In combination, a generator casing having a hand hole adjacent the brush mechanism, a flexible band adapted to encircle said generator casing to cover said hand hole, positive engaging members carried by the ends of said band, one of said members having an adjustable portion, whereby said members may be drawn toward each other to firmly clamp the band in position, said band comprising a fabric belt having a sheet metal backing riveted thereto, certain of 85 said rivets projecting inwardly and spaced apart a distance nearly equal to the length of said opening, in order to properly position said belt with respect to said generator casing.

5. A hand hole cover comprising a flexible band made up of a belt of compressible fabric and a metallic backing therefor, said elements being riveted together, four of said rivets projecting from the fabric side of 95 said belt in order to engage the end walls of two oppositely arranged openings in a generator casing to properly position said belt applied thereto, said belt having an adjustable wrench at one end and a co-operating 100 bracket at the other end, said wrench and said bracket having positive interlocking engagement when in adjusted position and adapted to be moved out of interlocking engagement upon slight adjustment of said adjustable wrench.

6. In combination, a dynamo electric machine casing provided with an inspection opening therethrough, a flexible strip encircling the casing and closing said opening 110 and means for positioning said strip circumferentially with respect to said casing to insure complete closure of said opening.

In witness whereof, I have hereunto subscribed my name in the presence of two witnesses.

WILLIAM E. BLISS.
